SUPPORTING DEVICE

Filed Sept. 26, 1930

UNITED STATES PATENT OFFICE

THOMAS M. KEEFE, OF BOSTON, MASSACHUSETTS, ASSIGNOR TO J. P. EUSTIS MANUFACTURING COMPANY, OF CAMBRIDGE, MASSACHUSETTS, A CORPORATION OF MASSACHUSETTS

SUPPORTING DEVICE

Application filed September 26, 1930. Serial No. 484,586.

The present invention relates to supporting devices of that type which is used for fastening and supporting fixtures, such as hardware, lighting fixtures, and, especially, 5 lavatory and bathroom accessories, to wall surfaces, whether of marble, tile, glass, cement, concrete, brick, plaster or wood. In this type of supporting device the means for fastening and supporting are usually concealed.

The architectural profession and interior decorators, as well as the public, demand fixtures for lavatories and bathrooms and interior decorative purposes, particularly, to have exposed surfaces which are free from 15 crevices, obtrusive screws, etc., which afford lodging places for dirt and bacteria, and which fixtures may be quickly and symmetrically mounted, and which remain rigid and 20 secure in the positions in which they are fixed.

The difficulties with concealed screw attachments now available are many, in some cases more, and in others less; for example, there are prior devices of this type wherein 25 set-screws are employed for the purpose of securing a supported part to a supporting part, in such a way as to conceal the screws which enter the wall or surface to which the entire device is fastened, such set-screws 30 tending to force the stem of the supporting part against the top, or some other point of the socket in the fixture or supported part, and throws out of align the base surface of the flange of the supporting device. Also, 35 the objectionable feature is encountered, in that the holding strain is not evenly distributed in the fixture socket or on the supporting device stem, but comes mostly on the set-screw.

40 The present invention aims to overcome such difficulties and to present certain advantages, for example, the following: the supporting device can be quickly fastened to a wall with wood screws, expansion bolts, expansion 45 shields, toggle bolts, or any of the devices commonly used for such purpose; in a few moments the fixture may be assembled with, and fastened to, the supporting device, so that the base of the fixture will be brought 50 in close contact with the wall and there held

immovable and secure by expanding the specially constructed stem of the supporting device into the socket of the supported part or fixture; and the supporting device lines up with the base of the fixture, thereby presenting a symmetrical disposition of the mutually attached parts.

The above being among the many objects and advantages of the present invention, the same consists of certain features of construction and combinations of parts, to be herein-after described and then claimed with reference to the accompanying drawing illustrating desirable embodiments of the invention, and wherein:

Fig. 1 is a sectional elevation illustrating a preferred embodiment of the invention;

Fig. 2 is a side elevation of the supporting part or member shown in Fig. 1;

Fig. 3 is an elevation of the supporting 70 part, as viewed from the terminal of its stem;

Fig. 4 is a transverse cross-section of the connected supporting and supported parts or members;

Fig. 5 is a fragmentary sectional view of 75 the complete assembled device, the section being taken at right angles to the section in Fig. 1;

Fig. 6 is a sectional elevation of a modified construction;

Fig. 7 is a side elevation of the supporting 80 part or member shown in Fig. 6, the view being taken at right angles to that figure; and

Fig. 8 is a transverse section on the line 85 8—8, Fig. 6.

Referring to Figs. 1 to 5, inclusive, there is shown the preferred embodiment of the invention in connection with a hook, but of course the assembled device may take any desired exterior form to adapt it for any purpose for which the device is suitable. The base 10, is preferably of disk shape and the stem 11, extends centrally from the base 10, these parts being preferably integral, so as to constitute a one-piece supporting part or member. The base 10, is provided on that face from which the preferably cylindrical stem 11 projects, with a stud 12, parallel with stem 11. The base 10, is also usually provided with two screw-holes 13, 13, one at each 90 95 100

side of the stem 11, so that the said holes and the stem are in line. In the present instance the stud 12, is located on a line with respect to the stem, which line is at right angles to the line of the stem and the screw-holes, and it serves as a positioning-member, as will appear herein.

Stem 11, of the supporting part or member, is provided at its outer end portion with 10 a transverse diametrical slot 14, which constitutes a gap with three open sides, that is to say, the gap is open at diametrically opposite sides of the stud 11, and is also open at the terminal of the stem, whereby the stem is 15 preferably bifurcated, so as to form bifurcations 15, 15. These bifurcations may be pressed apart slightly and, when the pressure is removed, they being resilient will return to their original positions, the stem 11, as well 20 as the other parts of the assembled device being made of metal, such as brass or steel. In order to provide a desirable expansion-action, a diametrical hole 9, is formed in the stem 11, at the points from which the bifurcations 25 15, 15, emerge, that is to say, at the bases of the bifurcations.

In the circumference of the stem 11, so as to be located at opposite sides of the gap 14, there are formed the bevel surfaces 16, 16, 30 these being so formed at the adjacent edge portions of the bifurcations 15, 15, as to flare outwardly away from the longitudinal axis of the stem, as clearly shown in Fig. 3. It will be seen that the gap 14, bisects the stem 11, and that the bevel surfaces 16, 16, form obtuse angles with the surfaces at opposite sides of the gap 14. It will also be noted that the gap 14, lies preferably in a plane which passes through the stud 12 of the base 10.

40 The supported member 17, of any suitable form, is provided with an enlarged base 18, which is formed with a recess 18a, which is adapted to snugly receive the base 10, of the supporting part. A preferably cylindrical bore 19, is formed in the supported part 17, 45 18, which extends longitudinal to the base 18, or at right angles thereto, so as to receive the stem 11. Preferably the bore 19 is considerably longer than the stem, as shown in Fig. 1, and when the parts are fitted together, there will be a very snug fit between that portion of the stem which lies between the base 10, and the bifurcations 15, 15, and that portion of the bore 19, which directly 55 surrounds said portion of the stem.

As shown in Figs. 1 and 4, the bore 19 is enlarged as at 20, this being done by counter-boring. The enlargement 20 is also preferably cylindrical, and its diameter need only 60 be very slightly in excess of the diameter of the stem 11, such excess diameter allowing for the expansion of the stem, that is to say, the spreading apart of the bifurcations 15, 15. In the drawing the enlargement 20, is 65 shown greatly exaggerated from what is

needed in practice, for the sake of making clear this portion of the invention. In practice it has been satisfactorily proven that an expansion of the bifurcations to as low as .0025 is satisfactory, although the degree of 70 permitted expansion may be greater, expansions to as high as .009 having proven entirely satisfactory. However, it is to be clearly understood that within practical requirements there is no limit to the degree of expansion, providing the objects and aims of the present invention are accomplished.

A lateral screw-hole 21, is formed in the shank of the supported part 17, in such position as that, when the stem 11, is properly positioned in the bore 19, the plane in which the gap 14 lies, will bisect the hole 21. This means that when a set-screw 22, having a tapered and pointed portion 23, is screwed into the hole 21, the tapered surface 23, will 80 be in bearing relation to the bevel surfaces 16, 16, of the bifurcations, and that the point of the screw will be entered in the gap 14, as more clearly shown in Fig. 4. It will be observed that when, as indicated in Fig. 5, the 85 screw 22, has been screwed home, the bifurcations 15, 15 are slightly spread apart into the enlargement 20, the transverse hole 9, permitting the desired quality of expansion. This securely locks the assembled parts together. It will be noticed that the screw-hole and the set-screw 22, are located in an unobtrusive position at the bottom of the shank of the supported part or bracket.

90 It will be apparent that in making practical use of the illustrated and described preferred embodiment of the invention, the supporting part is first attached in any suitable manner to a wall, as by screws having heads which are counter-sunk in the screw-holes 13, 13. When the supporting part is secured in position, its stud 12, will be vertically below the stem 11. The part to be supported is provided with a socket 12a, which is adapted to receive the stud 12. In assembling the parts, 100 care is taken that when the stem 11 is caused to enter the bore 19, the socket 12a will be in position so that the stud 12 will enter it, thereby preventing a twisting movement of the supported part around the base 10 and 105 stem 11. When the parts are so assembled, the bifurcations 15, 15, will extend into the enlargement 20, and the gap 14, together with the bevel surfaces 16, 16, will be in opposed 110 relation to the set-screw 22. At the moment of assembling the parts, the set-screw 22 is 115 preferably slightly out, sufficiently so that the bevel surfaces 16, 16, will easily glide along the tapered surface of the set-screw. The supported part being now in position, the 120 set-screw 22 is turned home so as to cause the point of its taper 23, to enter between the adjacent directly-opposed surfaces of the bifurcations 15, 15, and the tapered surface 23, to bear upon the bevel surfaces 16, 16, there- 130

by spreading the bifurcations apart into the slight enlargement of the bore 19. Thus the assembled parts will be firmly and positively locked together.

- 5 The tendency of the expansion-action on the bifurcations not only locks the members together, but it is apparent that this will act in a manner to pull the two assembled parts together, and one axially of the other there-
 10 10 by forming a close and desirable contact of the surface of the base 18, with the wall to which the assembled parts are attached. The action described is obvious when it is borne in mind that the point of first contact
 15 15 between the stem and the supported member, upon expansion of the bifurcations 15 of the stem, is where the expanded bifurcations of the stem is brought into contact with that portion of the supported member where its
 20 20 bore is smaller, so that continued expansion will exert endwise pressure on the supported member in the direction of its base and thus move said member axially of the stem and make close contact with the wall to which the
 25 25 assembled parts are attached, as stated.

In the modification of the invention illustrated in Figs. 6, 7 and 8, the same reference numerals are employed for those features which correspond to similar features in 30 the preferred embodiment of the invention. In the modification, the slot or gap 24, slightly differs from the gap 14. In the modification the gap 24, gradually widens towards the terminal of the stem, due to the fact that
 35 35 the stem is cut away, as at 25, so as to form inclines away from the longitudinal axis of the stem, and outwardly toward its terminal. As will be seen, the cut-out portion at 25 gradually enlarge inwardly (see Fig. 7), to-
 40 40 wards the diametrical hole 26, from which the bifurcations of the stem spring. As shown, the cut-away portions 25 at adjacent edges of the bifurcations, are beveled, as in-
 45 45 dicated by 27, so that there will be a bevel surface at each side of the taper of the set-
 screw 22. It will be apparent that the prin-
 ciple of expansion of the stem is substantially the same as in the principal form of the in-
 50 50 vention, but it will be also clear that by rea-
 son of the inclined surfaces at 25, 25, the tapered end of the set-screw will have a some-
 what increased tendency to draw the assem-
 bled parts together longitudinally of the stem.

55 On referring to Figs. 5 and 7, it will be seen that the transverse hole 9 in the first figure and the transverse hole 26 in the sec-
 ond figure are either partially or wholly with-
 in the snug-fitting parts of the supporting
 60 60 and supported members. This demonstrates
 that the first point of firm contact in expand-
 ing the bifurcations is within, and at the end
 of, the snug-fitting portion of bore 19 and
 is not within the enlargement of the bore.
 65 It is clear that if such transverse hole is with-

in the said snug-fitting portion to a less ex-
 tent than is shown in Fig. 5, a desirable re-
 sistance is afforded at the bases of the bifur-
 cations, it being only necessary to have a
 small portion of the said transverse hole, or
 70 that terminal of the slot, within the snug-fitting
 bore.

It will be obvious to those skilled in the art,
 that the illustrated and described invention
 is susceptible to more or less modification,
 75 and to still be within the appended claims.

What I claim as new is:

1. A supporting device comprising a tubu-
 lar member having at one end a substantially
 80 flat base for abutment against a body stand-
 ing perpendicularly to the axis of the member
 and having a bore of varying diameter, and
 a stem having means for attachment to an
 abutment and formed with a longitudinally
 85 extending gap to produce oppositely dis-
 posed portions adapted to be spread apart,
 said tubular member being mounted upon
 said stem and axially slidable thereon and
 formed with a screw-threaded hole bisected
 90 by the plane in which the gap extends, and
 a screw fitted in said screw-threaded hole and
 formed with a tapered terminal positioned
 to lie within the gap formed in the stem and
 bear against opposite walls of the separated
 95 portions of the stem, and functioning to
 spread apart said portions within the larger
 diameter of the bore of the tubular member
 and also move the tubular member axially of
 said stem.

2. A supporting device comprising a mem-
 ber formed with a longitudinally extending
 bore of varying diameter lengthwise of the
 member, and a stem having means for attach-
 ment to an abutment and formed with a lon-
 gitudinally extending gap to produce oppo-
 sitely disposed portions adapted to be spread
 apart, said gap terminating short of one end
 of the stem to form a part to fit snugly with-
 in the smaller diameter of the bore, said tubu-
 lar formed member being mounted on said
 100 stem and axially slidable thereon and formed
 with a screw-threaded hole bisected by the
 plane in which the gap extends, and a screw
 fitted in said screw-threaded hole and formed
 with a tapered terminal positioned to lie
 105 within the gap formed in the stem and bear
 against opposite walls of the separated por-
 tions of the stem and when screwed-up serv-
 ing to spread said separated portions in the
 110 larger diameter of the bore of the tubular
 member and also move the tubular member
 axially of the stem.

3. A supporting device comprising a mem-
 ber formed with a longitudinally extending
 bore of varying diameter, and a stem formed
 with a longitudinally extending gap to pro-
 duce oppositely disposed portions adapted
 to be spread apart, said gap terminating short
 of one end of the stem to form a part to fit
 snugly within the smaller diameter of the
 115 120 125 130

bore of said tubular formed member, and formed with a hole extending diametrically of the stem and positioned to fit at least partially within the smaller diameter of the bore of the tubular member, said tubular member being formed with a screw-threaded hole bisected by the plane in which the gap extends, and a screw fitted in said screw-threaded hole and formed with a tapered terminal positioned to lie within the gap formed in the stem and bear against opposite walls of the separated portions of the stem and adapted when screwed-up to spread said separated portions in the larger diameter of the bore of the tubular member and also expand a portion of the stem fitting in the smaller diameter of the bore of the tubular member and functioning to move the tubular member axially of the stem.
